UNITED STATES PATENT OFFICE.

ALONZO CONNELLY, OF TOPEKA, KANSAS.

STOVE DAMPER.

1,402,214.

Specification of Letters Patent.

Patented Jan. 3, 1922.

Application filed February 3, 1921. Serial No. 442,155.

To all whom it may concern:

Be it known that I, ALONZO CONNELLY, a citizen of the United States, residing at Topeka, in the county of Shawnee and State of Kansas, have invented certain new and useful Improvements in Stove Dampers, of which the following is a specification, reference being had therein to the accompanying drawings.

10 This invention relates to improvements in dampers, and particularly to a damper to be used in the pipe leading from a stove to a flue.

15 The object of the invention is the construction of a simple and efficient damper which will retard the escapement of heat from a stove and yet will allow the obnoxious gases or fumes to readily escape to the outer atmosphere.

20 With this and other objects in view, my invention comprises certain novel combinations, constructions and arrangements of parts as will be hereinafter described, illustrated in the accompanying drawing, and 25 more particularly pointed out in the appended claim.

In the drawing:

Figure 1 is a view of a stove to which is attached a pipe leading to a flue, the pipe 30 being broken away, showing my improved damper therein in elevation.

Figure 2 is a vertical, sectional view of my damper.

Figure 3 is a plan view of the ring of the 35 damper.

Referring to the drawing by numerals, 1 designates the stove, 2 the pipe, and 3 designates the flue. In the pipe 2 is positioned the damper 4.

40 The damper 4 comprises an annular ring 5, provided with penetrating spurs 6; these spurs 6 are adapted to be forced through the

walls of the pipe 2 to retain the damper in position within the pipe. Secured to the under face of ring 5 is the retarding cone-drum 45 7. Positioned above the ring 5 is an apertured cone 8, which cone 8 is provided with an annular flange 9; the flange 9 engaging the upper face of ring 5, thereby affording an efficient bearing, enabling the cone to rest 50 upon the ring 5.

The suction or draft through the apertured cone 8 is sufficient to draw the burned gases or fumes through the damper, yet the heat units will be retarded considerably by 55 striking against retarding cone-drum 7 and the apertured cone 8, heating the damper and thence heating the pipe to a greater degree because the metal damper and pipe will give off the heat to a greater extent than 60 would be the case if the pipe was left free by reason of no damper being therein.

While I have described the preferred embodiment of my invention, and have illustrated the same in the accompanying drawing, certain minor changes or alterations 65 may appear to one skilled in the art to which this invention relates, during the extensive manufacture of the same and I, therefore, reserve the right to make such alterations or 70 changes as shall fairly fall within the scope of the appended claim.

What I claim is:

As a new article of manufacture, a damper comprising an annular flat ring provided at 75 opposite portions with penetrating spurs, a retarding cone-drum engaging the under face of said ring, and an apertured cone provided with an annular flat flange resting upon the upper face of said ring. 80

In testimony whereof I hereunto affix my signature.

ALONZO CONNELLY.
